CLAIM

The ornamental design for a cutting and crimping jaw, as shown and described.

DESCRIPTION

FIG. 1 is a top front left-side perspective view of a cutting and crimping jaw of the present invention;

FIG. 2 is another top front right-side perspective view of the cutting and crimping jaw shown in FIG. 1;

FIG. 3 is a bottom back perspective view of the cutting and crimping jaw shown in FIG. 1;

FIG. 4 is a front elevational view of the cutting and crimping jaw shown in FIG. 1;

FIG. 5 is a back elevational view of the cutting and crimping jaw shown in FIG. 1;

FIG. 6 is a left-side elevational view of the cutting and crimping jaw shown in FIG. 1;

FIG. 7 is a right-side elevational view of the cutting and crimping jaw shown in FIG. 1;

FIG. 8 is a top elevational view of the cutting and crimping jaw shown in FIG. 1; and,

FIG. 9 is a bottom elevational view of the cutting and crimping jaw shown in FIG. 1.

The broken lines represent portions of the cutting and crimping jaw that form no part of the claimed design.
